UNITED STATES PATENT OFFICE.

ISAAC GARZON FORERO, OF BOGOTA, COLOMBIA.

FIRE-FIGHTING SYSTEM.

Application filed August 24, 1923. Serial No. 659,123.

The present invention relates to an improved fire alarm and fire extinguishing system, and includes improvements in the various devices themselves.

5 One of the objects of the invention is to provide for extinguishing fires without the use of water. A further object is to provide an adjustable thermostatic control for alarm and extinguisher and a carbon dioxide alarm. 10 In fighting fires, it is of great importance to attack the fire at its start. There are several decided disadvantages to the present systems using water sprinklers controlled by fusible links. The use of water causes considerable damage to goods stored and may frequently exceed the damage by fire. Water is also unsuitable in combating oil fires and fires where calcium carbide or similar chemicals are present. The sprinkler systems are 15 also designed to operate at one temperature only and are not adjustable.

In the applicant's invention no water is used and the thermostatic control is adjustable, since the temperature which would indicate a fire in an unheated warehouse in the winter is much lower than in the case of the same warehouse on a hot day. The invention will be more fully described with reference to the accompanying drawings in 20 which Figs. 1 and 2 show elevations of two sides of the thermostatic device and carbon dioxide alarm.

Fig. 3 is a horizontal section taken along the line 3—3 of Fig. 1.

35 Fig. 4 is a vertical section through the thermostat taken along the line 4—4 of Fig. 3.

Fig. 5 is an elevation of a central alarm board.

40 Fig. 6 shows an elevation of the extinguishing apparatus and oxygen exhausting pump.

Fig. 7 is a section through a different type of oxygen exhausting pump.

45 In the embodiment shown in the drawing four thermometers 1 A—D are held in a rectangular box 2. Three of the thermometers 1 B—D are of the form shown in Figs. 2 and 4 and serve to operate the extinguisher, 50 annunciator and general alarm. One of the thermometers 1 A is of the design shown in Fig. 1 and operates the bells 19 shown in Fig. 5. 3 is a carbon dioxide alarm, consisting of a U tube filled with mercury and 55 closed by a stopper at 4. The other end is an enlarged funnel covered by a slab 5 of

unglazed porcelain, gypsum or other porous material which permits the lighter gases, such as oxygen, to pass through, but hinders the passage of carbon dioxide. The contacts 60 are sealed in the glass of the U tube.

In the thermometer shown in Fig. 1, 7 is the main switch and at 8 are shown individual switches for the contacts 9, which are sealed into the thermometer tube. The wiring is indicated diagrammatically by broken lines, the wires running from the individual switches 8 through a conduit 7' to the bells 19, shown in Fig. 5. This conduit carries the wires from the box 2 to a central station 70 as described below, and also wires from thermometer 1 D which are branched from the conduit to connect with the fire-extinguishing apparatus shown in Fig. 6.

The thermometer indicator shown in Figs. 75 2 and 4 consist of a thermometer 1 C, a number of contact pairs 10 sealed in the thermometer tube, a slide 11 carrying contacts 12 and sliding in the slots 13 making contact with certain of the plates 10' (all clearly 80 shown in Figs. 3 and 4). Two wires run from the contacts 12, as shown in Fig. 4. The contacts 10—10' are in series with the bell 15 and the battery 14. In practice it is preferable to interpose relays between the 85 actual alarm devices and the thermometer circuit in order to protect the latter.

The carbon dioxide indicator has a contact 16 at the bottom of the mercury column and a plurality of contacts 6 which are normally above the mercury column, but which progressively make contact with it as the column rises due to the increase of the carbon dioxide content in the air. The carbon dioxide indicator controls the bells 17, each 95 contact 6 controlling a separate bell. The bells preferably have different tones so that the amount of carbon dioxide in the air is indicated by the tone of the bell. The lowest contact 6 is preferably also connected 100 with the annunciator 20 which indicates from which room the alarm proceeds.

The gaps in the thermometer 1 B are in circuit with the annunciator 20, and when closed cause that number to appear which corresponds to the room in which the thermometer is situated. Similarly thermometer 1 D controls the fire extinguishing device shown in Fig. 6. The telephone circuit 18 may be closed by the operation of 110 either the thermometers 1 A or 1 B, or the carbon dioxide indicator. When closed this

circuit enables the sound of the bells on the board to be heard at the central telephone office.

The fire extinguishing apparatus in Fig. 6 consists of a motor 21, driving a centrifugal pump 22, having an intake through a porous procelain or gypsum block 23. The exhaust pipe 24 extends into the open air outside the room in which the apparatus is set up. The opposite end of the motor shaft carries a bevel pinion 25, meshing with another bevel pinion 26, attached to the shaft 27. The upper end of the shaft carries a bevel pinion 28, meshing with the bevel pinion 29 which turns a fork 30. 32 is a cylinder for compressed gas, and 31 is the valve of the cylinder. 33 and 34 are springs which tend to rock the shaft 27 so as to throw the pinion 26 out of mesh. 35 is a flexible journal, and 36 is a bumper.

The cylinder 32 is supported above a shallow open box 37 and is inclined somewhat so that when the valve is opened the liquid carbon dioxide will be at once forced out into the box. The pipes 38 serve to carry off a small portion of the liquid carbon dioxide and are preferably run around the cracks of the windows or doors of the room in which the extinguisher is situated. Thermostatic elements may also be associated with the pipes in order to close the windows or doors. Any conventional type of thermostat or thermostatic relay may be used except that in the case of a liquid filled type a gas boiling above the boiling point of carbon dioxide must be used instead of a liquid.

Fig. 7 illustrates a modified exhauster pump showing a two cylinder plunger suction pump instead of a centrifugal pump. The particular design of the suction pump is a conventional one, and in itself forms no part of the applicant's invention.

The operation of the system is as follows:

Each room which is to be protected has a thermal indicator and an extinguishing device. At a central part of the building, for example the watchman's room, is mounted the board illustrated in Fig. 5. The slides on the thermometers are set at the desired temperature, which will in general be higher in summer than in winter. The main switch 7 is closed and such of the individual temperature switches 8 as are desired are also closed. In general, switches will be closed for lower temperatures on thermometers 1 A and 1 B than on the other two thermometers.

When a fire starts the temperature rises and the amount of carbon dioxide in the atmosphere increases. In the case of a smouldering fire, the temperature may not rise high enough to set off the thermal alarms, but the increase in carbon dioxide in the air will cause the mercury column to

rise in the carbon dioxide alarm 3 as the gases inside the apparatus diffuse out through the porous plate 5 faster than carbon dioxide diffuses into the apparatus, and a pressure differential arises so that the mercury column is moved and makes contact with the contacts 6. Usually, however, in case of fire the temperature rises rapidly. As soon as the mercury column in thermometers 1 A and 1 B reaches the first contact 75 with a closed switch the circuit is completed and rings one of the bells 19 corresponding to the particular contact 9 and also operates the annunciator 20 causing the number corresponding to the room to appear. The 80 bells 19 preferably have different tones so that the watchman can tell the temperature by the tones of the bell's ring.

When the temperature rises still further contact is made in the thermometers 1 C 85 and 1 D and the various circuits are closed so that the bell 15 rings. As the telephone circuit is also closed the telephone central can hear the bells and turn in an alarm in case the watchman does not respond to the 90 call. Manual switches may be provided whereby the watchman can open the bell circuits to indicate that he is attending to the fire.

The circuit through the extinguisher is also 95 closed, preferably through a relay, and the motor 21 is started. The shaft 27 is rotated which in turn unscrews the valve 31 of the gas cylinder 32. This cylinder is preferably filled 100 with a carbon dioxide. Nitrogen may also be used, but is less efficient than carbon dioxide since it is not so readily separated from oxygen by the exhauster. As soon as the valve is opened the liquid carbon dioxide is forced out owing to the inclination of the cylinder 105 32 and fills the shallow box 37 where it evaporates very rapidly due to the large surface. Part of the liquid flows down the tubes 38 and chills them.

When the valve 31 is completely unscrewed the shaft 27 is free to move by the pressure of the springs 33 and 34 thereby throwing the pinion 26 out of mesh. The bumper 36 prevents the pinion 25 from striking 110 the motor.

The operation of the exhauster is as follows:

The pump creates a vacuum and as the plate 23 is pervious to the lighter gases, such as oxygen these are sucked out while to a 115 large extent carbon dioxide or other heavy gases remain behind. The action of the exhauster is, therefore, to rapidly decrease the content of oxygen in the room leaving carbon dioxide behind. This will soon extinguish the fire because of lack of oxygen.

The use of carbon dioxide has the further advantage that as the liquefied gas expands it is powerfully cooled and portions of it may even solidify. The strong chilling has 120

the effect of cooling the combustible substances below the point of ignition and this aids in putting out the fire. The cold fluid in the tubes 38 tends to close any cracks around doors and windows as the moisture from the inrushing air freezes and forms a hermetic seal around the windows or other openings. This is of considerable importance as the operation of the pump tends to lower the pressure in the room and it is undesirable to have any air taken in from outside on account of the oxygen introduced. If desired, the fluid carbon dioxide may be made to operate thermostatic devices for closing windows or doors, or the thermometer circuits may be arranged to actuate an electrical closing means for the windows or doors. The carbon dioxide cylinder is preferably placed high up as the gas is heavier than air and will sink on the fire as a blanket.

In the detailed description separate thermometers have been shown for ringing an alarm, working the annunciator and starting the extinguishing system. The use of several thermometers is advisable to minimize the chances of one of them failing, but a single thermometer can be used to perform the functions of the two thermometers 1 C and D if desired. The electrical connections have merely been indicated diagrammatically and may be considerably varied. For example, the two thermometers 1 C and D may be connected in parallel so that either of them will operate the alarm and the fire extinguisher. Thermometer 1 A may also be made to operate the annunciator in parallel with thermometer 1 B and other changes in electrical connections may be made where the exigencies of the particular system make them desirable. The system of the present invention is not only sufficient, but is very flexible and may be adapted to almost any building which it is desired to protect. The extinguishing agent used is unaffected by cold and is equally efficient in extinguishing the various types of fires.

While one of the notable advantages of the present system is that it does not require water, it may be used in combination with water, if desired, and not only does not detract from the effectiveness of the water, but actually enhances it as the chilling resulting from the expansion and evaporating of the gas tends to freeze the water and forms coatings of ice over the combustibles. In some cases where the combustible materials are not seriously injured by water a sheath of ice may be formed by providing extensions to the carbon dioxide pipes 38 running in close proximity to the combustible material. When the water is turned on the intense cold produced by the evaporation of the liquid carbon dioxide in these pipes will rapidly form a sheath of ice over the combustible material.

In the claims the term "non-oxidizing gas" is used to cover any gas which is incapable of supporting combustion as the longer expression is awkward.

I claim:

1. In a fire-fighting system, a fire-extinguishing device comprising in combination a motor, a device driven therefrom adapted to reduce the percent of oxygen in the atmosphere surrounding the fire by removing oxygen therefrom, a valved tank for compressed non-oxidizing gas, means operated by said motor for actuating the discharge valve of the tank, and conducting means from said discharge to said atmosphere. 70

2. In a fire fighting system, a fire-extinguishing device, comprising in combination a motor, a pump driven by the motor, an air inlet to the pump more pervious to oxygen than to carbon dioxide, and an exhaust from the pump into the open air. 80

3. In a fire fighting system, a fire-extinguishing device comprising in combination a motor, a pump driven by the motor, an air inlet to the pump consisting of a block 90 of unglazed porcelain, and an exhaust from the pump into the open air.

4. In a fire fighting system a fire extinguishing device, comprising in combination a motor, a pump driven by the motor, an air inlet to the pump consisting of a block of unglazed porcelain and an exhaust from the pump into the open air, a tank for compressed gas and means for discharging said tank operated by the motor, and automatic 100 means for breaking the driving connection between the motor and the tank valve when the latter is fully opened. 95

5. In a fire fighting system a fire extinguishing device, comprising in combination 105 a motor, a pump driven therefrom, having an inlet consisting of a porous unglazed porcelain block and an exhaust to the open air, a tank for compressed gas, a valve in said tank operated by a fork, a shaft driving said fork through a set of bevelled gears, said shaft being driven by the motor through a second set of bevelled gears, a flexible journal near the center of the shaft and a pair of springs tending to rock the shaft so that the second set of gears are thrown out of mesh when the valve is fully opened. 115

6. In a fire fighting system, a fire-extinguishing device comprising in combination a motor, a pump driven therefrom, having an inlet consisting of a porous unglazed porcelain block and an exhaust to the open air, a tank for compressed non-oxidizing gas, a valve in said tank operated by the motor, a shallow pan with conducting pipes leading therefrom adapted to receive the contents of the tank when the valve is released. 120

In testimony whereof I affix my signature.

ISAAC GARZON FORERO.
